UNITED STATES PATENT OFFICE.

FREDERICK H. MARTIN, OF AKRON, OHIO, ASSIGNOR TO THE B. F. GOODRICH COMPANY, OF NEW YORK, N. Y., A CORPORATION OF NEW YORK.

OVERBOOT.

Application filed April 8, 1922. Serial No. 550,633.

To all whom it may concern:

Be it known that I, FREDERICK H. MARTIN, a citizen of the United States, residing at Akron, in the county of Summit and State 5 of Ohio, have invented a certain new and useful Overboot, of which the following is a specification.

This invention relates to the construction of footwear, particularly of that type having a waterproof foot and an upper of cloth or rubberized cloth, although other materials can be used.

My object is to provide an improved overboot or shoe adapted to take the place of galoshes, and so constructed as to be readily applied and removed, but dispensing with the usual flap quarters and fastenings.

Of the accompanying drawings, Fig. 1 is a side elevation, partly in section, showing an over-boot constructed according to my invention.

Fig. 2 is an enlarged perspective view of the top of the boot, with the cuff flap unfastened.

In the drawings, 10 is the foot portion of the boot, constructed like an ordinary over-shoe with a rubber sole and facing, and 11 is the top or leg portion integrally joined to the foot and constructed of the ordinary 20 materials used for galoshes, such as cloth frictioned on the inner side with rubber and joined to a rubber-frictioned lining, together with the usual internal stays, extra lining pieces, etc., which it is not important 25 to show.

At the upper end of the leg is a cuff 12 normally folded down over the outside and having a flap 13 at one end adapted to underlap the other end of the cuff, the respective ends being provided with the members 40 14, 15 of an ordinary snap-fastener for securing them together in either the folded-down position shown in full lines, or the upturned position shown in broken lines in Fig. 1.

At a point underlying the cuff-flap 13 the boot-leg is vertically cleft or divided in a vent or V 16 to permit the temporary enlargement of its mouth and facilitate the 50 application and removal of the boot, and the edges of this cleft are connected with a small bellows tongue or pocket 17 to maintain a continuous wall and closure back of the cleft. The cuff-fastening and the vent are desirably located at the side of the boot-leg

as shown, although their position might be varied.

This boot is preferably worn as a protection over an ordinary leather shoe. In applying or removing it, the ends of the cuff 60 12 are unfastened as shown in Fig. 2, so that the vent 16 may open and enlarge the mouth. When the boot is in place, the flap 13 may be fastened under the other cuff-end with the cuff turned down, or the cuff 65 may be turned up as indicated by the broken lines in Fig. 1, and the flap then secured over the other end with the snap-fastener, in which latter case, particularly if the cuff is faced with some soft or fluffy material, considerable extra warmth and protection are 70 secured.

It will thus be seen that my invention provides an over-boot to take the place of galoshes, dispensing with the usual troublesome fastenings and presenting a neater 75 appearance. The details of construction may be variously modified.

I claim:

1. A boot having foot and leg portions, 80 a cuff at the top of the leg portion adapted to be turned downward against the leg portion or upward therefrom, and means for detachably connecting the ends of said cuff in either a folded-down or an upturned 85 position.

2. A boot having foot and leg portions, a turn-down cuff at the top of the leg portion having lapped ends, and means for detachably fastening said ends together. 90

3. A boot having foot and leg portions, a cuff at the top of the leg portion adapted to be turned downward against the leg portion or upward therefrom, said cuff having an end flap portion adapted to underlie the 95 other end portion of the cuff in the folded-down position of the latter and to overlie it in the up-turned position, and a snap-fastener for detachably connecting said end portions of the cuff. 100

4. A boot having a foot portion, a leg portion unbroken except for a cleft at its upper end, and a cuff having end portions having substantially the same vertical dimension as said cleft and positioned adjacent said cleft. 105

5. A boot having foot and leg portions, said leg portion provided with a cleft at its upper end, a bellows tongue connecting the edges of said cleft, and a cuff whose ends 110

have substantially the same vertical dimension as said cleft and are adapted to overlie one another adjacent said cleft.

6. A boot having a foot portion, a leg portion formed with a cleft at its upper end, a cuff adapted to be turned downward against the leg portion or upward therefrom, said cuff terminating at one end substantially at

one edge of said cleft and having a flap at its other end adapted to overlie said cleft 10 in the down-turned position of the cuff, and means for detachably connecting the cuff ends in lapped relation.

In witness whereof I have hereunto set my hand this 5th day of April, 1922.

FREDERICK H. MARTIN.
